UNITED STATES PATENT OFFICE.

EDGAR F. HATHAWAY, OF BOSTON, MASSACHUSETTS, ASSIGNOR TO AMERICAN WARP DRAWING MACHINE COMPANY, OF BOSTON, MASSACHUSETTS, A CORPORATION OF MAINE.

THREAD-UNITING MACHINE.

1,305,706.

Specification of Letters Patent.

Patented June 3, 1919.

Application filed February 14, 1906. Serial No. 301,018.

To all whom it may concern:

Be it known that I, EDGAR F. HATHAWAY, a citizen of the United States, residing at Boston, county of Suffolk, and State of 5 Massachusetts, have invented an Improvement in Thread-Uniting Machines, of which the following description, in connection with the accompanying drawings, is a specification, like letters on the drawings representing like parts.

10 My invention relates to improvements in thread-uniting machines and, as embodying one form thereof, I have herein illustrated the same with reference to a machine for uniting the free ends of one series of warp threads to those of another.

15 My invention will be best understood by reference to the following description, when taken in connection with the accompanying 20 drawings which show, for illustrative purposes, one specific embodiment thereof, while its scope will be more particularly pointed out in the appended claims.

In the drawings,—

25 Figure 1 is a front elevation of a thread-uniting machine embodying one form of my invention;

Fig. 2 is an end elevation of the same;

30 Fig. 3 is a detail in front elevation, partially broken away, showing one end of the base of the machine frame;

Fig. 4 is a plan view showing with reference to a loom the usual position of the same machine when in operation;

35 Fig. 5 is a central, longitudinal section taken through the friction driving device shown in Fig. 1;

Fig. 6 is an end view of a portion of the machine showing the driving mechanism 40 for the carriage compensating feed;

Fig. 7 is a front elevation of the parts shown in Fig. 6;

Fig. 8 is an enlarged detail in plan of parts shown in Fig. 6;

45 Fig. 9 is a side elevation of the same;

Fig. 10 is a perspective showing the relation of the two sets of warp threads to the uniting mechanism;

Fig. 11 is a plan view of the knotter carriage and knotter mechanism;

Fig. 12, a rear elevation of the same;

Fig. 13, an end view, partially in section;

Figs. 14, 15, 16 and 17 are enlarged details in plan showing the relation of parts

of the knotter mechanism during successive stages of the knot-tying operation;

Fig. 18 is a front elevation of the knotter during the completion of the knot-tying operation, and

Fig. 19 is a vertical section in elevation, 60 taken lengthwise the knotting device.

While certain features of the invention have application to machines adapted for purposes other than warp uniting the principal use of the illustrated embodiment of 65 my invention is to join the thread ends of an old warp, which has been in the loom to a new warp. And while certain features of the invention may be usefully employed in joining the ends of either a leased or unleased warp the mechanism herein described is particularly adapted to meet the requirements in the case of commercial warps where crosswise or transverse sections of the warps held between clamps or 70 other holding devices in unleased relation with the threads substantially parallel but irregularly spaced, are required to be united.

75 In the embodiment of my invention which I have here selected for illustration, the 80 thread ends of one warp, which may be supposed to be the old warp taken from the loom, and the thread ends of the second warp, which may be regarded as the new warp placed, or about to be placed, in the 85 loom, are held distended in two crosswise or transverse sections, grouped and arranged opposite each other and the uniting mechanism is caused to travel lengthwise the series 90 for the purpose of progressively acting thereon. It is of course to be understood that the movement of the uniting mechanism and the differential movements of the warp threads to be subsequently explained are required to be relative only, and that the 95 actual identity of the stationary elements or the movable elements is immaterial except as to simplicity of construction. In the following description, therefore, where certain elements are referred to as stationary and others as movable, or certain movements as horizontal, vertical or otherwise, it is to be understood that these terms relate specifically only to the machine disclosed and are not essential features of this invention.

100 The machine illustrated is provided with upright end standards a, a' , which are con-

nected (Fig. 4) by the base-plate a^2 , the said standards and base-plate being preferably of solid and substantial construction to afford a firm and suitable support for the 5 warp carriages and uniting mechanism. At its base each standard has the lateral semi-circular fender frame a^4 , (Figs. 3 and 4) to prevent injury to the standards or to other objects in moving the machine. The principal mechanisms of the latter are carried 10 upon a swinging head comprising the swinging end supports a^3 , a^4 , which are adjustably mounted so that the head may be tipped to some inclined position like that shown in 15 Fig. 2, or maintained in a vertical, upright position, as illustrated in Fig. 1.

For this purpose the end supports a^3 , a^4 , are mounted for swinging movement in trunnions journaled in the standards a , a' respectively, so that they may be swung thereon. Means for adjusting them to any desired position and there fixedly maintaining them, are provided through the segmental gears a^5 (Fig. 2) upon the lower end 25 of the two swinging supports a^3 , a^4 , the said gears meshing each with a pinion a^6 secured to a shaft upon one end of which adjacent the standard a is the worm gear. The worm gear a^7 can be turned by the worm a^8 and 30 the hand wheel a^9 to adjust the head to any desired inclination. This, as will be better understood when the employment of the machine with reference to the two warps is described, considerably facilitates its use, 35 since it may be moved with readiness in an upright position through narrow loom alleys, but, when in use, the head may be swung down and over the warp roll of a loom, securing a better position for the operating mechanism with reference to the 40 warp beam and the loom and with reference also to the position of the operator in front of the uniting machine. For ease in handling the base is mounted at each end upon 45 a pair of ball bearing casters a^{10} (Fig. 2). The machine is shown in Fig. 1 as broken away and therefore considerably shortened, but its actual length will of course be adequate to hold the widest warp.

50 The thread ends to be united may be supported in any suitable way, but herein the ends of the two warps are carried and held upon separate frames or carriages B, and C (Fig. 1), respectively, which are mounted 55 to hold the threads in proper position with reference to the uniting mechanism, and, in the disclosed form of machine, are also adjustably movable within certain limits lengthwise the machine.

60 The carriage B comprises the side or end members b united and supported by a rod b' , which is carried upon suitable roller supports b^2 , the latter journaled upon the swinging end supports a^3 , a^4 . At their 65 opposite or lower ends the said end members

are united by a similar rod b^3 , which is supported for sliding movement in the head of the machine. At the lower end of each end member (Fig. 2) is provided a yoke or jaw b^4 , in which is mounted upon the adjusting 70 screw b^5 , the clamping jaw b^6 , the latter adapted to receive one end of the clamping bar b^7 (Fig. 10) in which the warp threads of one warp (herein the old warp) may be clamped. 75

Upon the upper longitudinal carriage rod b' , and near opposite ends of the machine, are clamped the brackets b^8 , which have depending clamping jaw members b^9 (Fig. 2) which are adapted to receive a second bar 80 b^{10} (Fig. 10) upon which will customarily be clamped the extreme ends of the old warp threads.

The carriage C for supporting the remaining, and what will ordinarily be the 85 new warp, is constructed in substantially the same general fashion as the carriage B, but located and mounted upon the head so that its thread ends are held distended in a substantially parallel relation with reference to 90 the thread ends of the other warp and in front of the latter or at the left as viewed in Fig. 2. Further specific description of the parts comprising the carriage C is unnecessary, the corresponding parts being lettered with the same index numerals as the parts upon the carriage B. Obviously, if desired, for any reason, the position of the old and new warps might be reversed.

Successive threads in each warp, prior to 100 their seizure by the thread-uniting mechanism, are acted upon by suitable separating and selecting devices, which act first to select and then to separate the individual threads and present them in suitable alignment to the uniting devices. For this purpose there are provided two parallel rotatable shafts d and e extending lengthwise the machine. These are arranged adjacent to the uniting mechanism and when the respective warps are placed in position (see Fig. 10), the threads of the warp mounted upon the carriage B in leading from one clamping bar to the other pass over the separator shaft d , while the threads of the warp upon the carriage C pass over the separator shaft e . These shafts are removably journaled at one end in the swinging end piece a^8 and at the opposite end are removably splined in sleeves 110 which are journaled upon the opposite end frame member a^4 , the said sleeves carrying intermeshing gears d' and e' (Fig. 1) respectively, by which the two shafts are given 120 equal but opposite rotation.

The sleeve carrying the gear e' has also secured thereto the bevel gear f (Figs. 1, 6 and 7), meshing with the bevel gear f' upon the short inclined shaft f^2 , at the lower or opposite end of which is the bevel gear f^3 , 130

meshing with a similar gear f^4 upon the end of the main drive shaft g . The latter passes lengthwise the carriage and acts to impart periodic movement to the thread-uniting mechanism. The gear f^4 and the drive shaft in turn are driven by the bevel gear f^5 upon one end of the inclined shaft f^6 , to the lower or opposite end of which is secured the bevel gear f^7 , meshing with the gear f^8 , which latter is mounted upon and secured to the counter-shaft h , journaled horizontally in the fixed standard ends a, a' and having its axis coincident with the axis of tipping movement of the machine head, whereby the tipping adjustment of the latter does not affect the driving connection between the said counter-shaft and the described mechanism above.

Driving movement (Fig. 1) is imparted to the counter-shaft h through the sprocket wheel h' secured thereon, engaging with the sprocket chain h^2 , driven by the underlying sprocket wheel h^3 , the latter secured to the clutch member i , loosely mounted upon the main driving shaft i' but adapted to be clutched thereto through the sliding clutch member i^2 . When the clutch is thrown in, a constant rotation is given the driving shaft g and the separator shafts d and e .

Upon each separator shaft is a sliding sleeve which is provided with selecting and separating means for suitably selecting and separating the threads preparatory to knotting the same. The selecting and separating devices being of substantially the same construction, description of one only is necessary. Referring to the device for the shaft d , (Figs. 1 and 10) the same is in the form of a sleeve having a tapering nose d^2 , preferably corrugated for a portion of its length, and a separating screw d^3 , the latter provided with a spiral thread groove. The sleeve is provided with a feather or key fitting a seat or key-way extending lengthwise the shaft d , so that it may be rotated by the shaft while being propelled or slid lengthwise the same. To advance the thread selecting and separating device with the thread-uniting mechanism, there is provided a yoke d^5 (Fig. 10), which enters a groove in the separating sleeve, said yoke being connected to a bracket j mounted upon the carriage of the uniting mechanism to travel therewith. This permits the sleeve to turn freely in the yoke, while advancing therewith.

Since each set of warp threads are held stretched over a separating shaft when the warps are in position, the advance of each selecting and separating mechanism causes the threads of each series first to travel upon the inclined nose d^2 and under the resulting increased tension to be stroked by the corrugations into a position of parallelism. They are then engaged by the separating screw d^3 , the advancing lip of which singles

out each thread and selects it from the remaining ones, while the continuation of the groove of the worm or screw separates the selected thread still further and presents it at the proper time and place to the action of a thread-drawing device while it is held in proximity to and in substantial parallelism with the foremost thread of the remaining series. The selecting lip referred to is formed where the groove cuts through the slightly raised shoulder at the end of the threaded portion of the sleeve, and such raised shoulder bears against and moves across the edge of the sheet of unseparated warp threads, the lip acting to pick off the threads one by one as the rotation of the shaft d causes it to cut through the plane of the threads. The screw thread extends for a sufficient distance to hold separate a series of the threads prior to their engagement by the thread drawing device, so that the operator is enabled to check the accurate operation of each selecting and separating screw prior to the taking of the thread by the thread taking device.

The preferred operation of placing the two warps in the machine briefly is as follows: The extreme ends of the old warp before withdrawal through the harness are clamped upon the bar b^{10} (Fig. 10). This clamp bar consists of a light metal channel iron in which there is forced a clamping strip covered with rubber, felt or other suitable friction material.

The ends of the new warp which has been placed upon the warp beam of the loom are also clamped by a similar clamp bar c^{10} . The uniting machine which may be supposed to have its head adjusted to a vertical position to facilitate its transportation, is then moved to the loom and swung around with its back adjacent to the back of the loom, as indicated in Figs. 2 and 4, and the head of the machine swung down by means of the adjusting hand wheel a^9 to overhang the back of the loom. This position and relation places the machine directly back of, with its operating parts overhanging the loom, and occupying the minimum amount of additional space.

The separator shaft e and the clamping strip of the bar b^7 having been removed, the ends of the old warp are then placed in the machine in the general position indicated by the dotted lines (Fig. 2), the clamping bar b^8 being carried under the rod b^9 of the carriage B over the channel iron of the clamp bar b^7 and up and over the separator shaft d and placed in the clamping jaws b^9 . The clamping strip of the bar b^7 is then inserted to clamp the threads at that point. The other warp is likewise placed in the machine as shown in Fig. 2, the clamping bar c^{10} , however, being first carried up and laid on the rests K upon brackets b^8 . The separator

shaft c is then replaced, the clamp bar clamped in the jaws c^9 and the clamping strip inserted in the bar c^7 , so that the two groups of threads then present two substantially parallel stretches, as shown in Figs. 2 and 10, leading from the lower clamping bars up and over the separator shafts. When the thread ends are immovably clamped, the lower clamping bars are adjusted at each end by the adjusting screws b^5 , c^5 (Fig. 2) to suitably and evenly tension the threads across the separator shafts.

It will be obvious that the machine may be used on the floor, away and apart from the loom, if desired, but the construction of the machine disclosed makes it particularly adapted for use as described with a considerable saving in the time and labor of handling warps and harness in and out of the loom.

As a convenient means for imparting driving movement to the main driving shaft c , the latter is extended at each end (Fig. 1) through the frame member a , which latter is formed into a hub or sleeve a^{10} incasing the shaft end. A bracket a^{11} is provided having the sleeve portion a^{12} , in which is journaled the hub a^{13} of the bevel gear a^{14} . To the end of the gear hub is screwed the plate a^{15} which holds the gear upon the bracket. When the machine is in position, the sleeve of the bracket carrying the gear is slid within the hub a^{10} and there locked in place by the set screw a^{16} engaging a groove in the periphery of the sleeve. When the sleeve is inserted in the hub, a pin in the gear hub enters the split end of the shaft.

The bevel gear a^{14} engages with the driving pinion a^{17} (Fig. 2) which is mounted upon the shaft a^{18} journaled in the bearings upon the bracket a^{11} . When the machine is positioned near the loom the shaft a^{18} is connected (see Fig. 4) by the flexible coupling shaft a^{19} , which is driven from the bevel gears a^{20} mounted upon the bracket a^{21} clamped to the frame of the loom, said gears being in turn driven from a friction pulley a^{22} , which is caused to engage with the main driving belt of the loom. In the operation of the machine, the threads are first selected and separated and a pair of separated threads one from each warp are then engaged by thread placing mechanism herein in the form of a drawing needle which brings the threads side by side in operative relation to the knotter. The knotter then acts after which the free ends of the threads are severed and the united threads withdrawn from engagement with the uniting devices. This operation proceeds step by step until the entire series of threads has been united, when the entire series of united threads may be withdrawn from the machine.

65. Herein provision is made to permit the

knotting mechanism to act upon the individual threads of each series to be united irrespective of a difference or irregularity in spacing of the individual threads. In the form of separating device shown it is desirable for the effective action of the selecting device that each warp thread engage the lip of the screw at substantially the same angle. In practice however commercial warps are not only irregularly spaced but the two warp sections to be joined are seldom of the same width and spacing. If one has already been in the loom it will usually be narrower and more closely spaced than the other. If both are maintained stationary therefore the advance of the knotting mechanism will cause the threads of one warp to bear a varying and increasingly different relation to the selecting device and to the operating mechanism from the threads of the other warp.

Whether this specific mode of thread separation is employed or not, or whether the alinement of the threads is considered with reference to some other part of the uniting mechanism, it will be evident that some approximately certain relation should be maintained between the warp threads and the uniting mechanism considered as a whole.

One feature of this invention is to provide means for correcting this variation in alinement arising from difference in width of the warps and to adapt or compensate the action of the knotting mechanism to the different or irregular spacing of the individual warp threads.

The adjustment of these several elements, the two warps and the uniting mechanism, for the difference in the width of the warps may be effected in a variety of ways, as for example by imparting to any one of the elements any suitable movement which will correct for the difference. In the present machine, however, I preferably adjust the rate of advance of the uniting mechanism with reference to one of the warps, and preferably the narrower one with as close an approximation as is practicable and to impart in addition a slight differential movement to the carriage of the remaining warp in the opposite direction to the advance of the carriage, which movement is proportioned to correct for the difference in the widths of the two warps. The differential movement in the present machine may be imparted to the warp carriages, either manually or mechanically at will although either mechanical or manual movement alone might be relied upon, if desired.

Referring now more particularly to means by which this is accomplished: The two warp carriages, as before stated, having limited movement lengthwise the machine, carry each an appropriately toothed rack, which herein is formed in the under side

of the lower carriage rods b^3 , c^3 (Fig. 7). Upon the swinging end frame member a^4 are journaled worms l , l' , adapted to engage respectively the rack teeth upon the carriages C and B, the worms being provided with attached driving gears l^2 and l^3 , respectively.

While these pinions might be constantly driven during the operation of the machine, 10 to give a continued differential movement to each carriage, the same are herein driven, one to the exclusion of the other, through the small gear l^4 which is mounted (Fig. 6) upon the arm l^5 , whereby it may be swung 15 into or out of engagement with either one of the two pinions. The arm l^5 is journaled for swinging movement upon the rod l^6 and has an attached arm l^7 , the latter at its lower end providing a journal support for 20 the shaft l^8 , fixedly secured to one end of the hand rod l^9 which extends lengthwise the machine, and at its opposite end is also 25 swingingly supported upon the rod l^{10} pivoted on the rod l^6 , so that by merely raising or lowering the hand rod, the pinion l^4 is 30 thrown into driving mesh with the upper or lower of the two gears l^3 and l^4 , respectively. A spring-pressed pin l^{11} in the frame bearing against the projection l^{12} upon the side 35 of the arm l^7 retains the rod in either assigned position up or down.

The compensating pinion l^4 is mechanically driven through driving mechanism which also operates the lead screw for the 35 advance of the uniting mechanism. This driving mechanism is provided with means for manually adjusting its speed in proportion to the slay of the warp, so that where the number of threads per inch is greater in 40 one case than another, the advance of the uniting carriage, as well as the movement of the warp carriage may be lessened.

For this purpose (Fig. 1) the counter-shaft h is extended to overlie the friction 45 disk m , the latter journaled in the bracket m' , fixedly secured to the machine frame and having frictional engagement (Figs. 1 and 5) with a friction roll m^2 on the end of the counter-shaft. The latter is mounted to 50 have sliding movement lengthwise the shaft h , which at this point is tubular, but is driven by the pin m^3 , which passes through a longitudinal opening in the tubular shaft and is connected to the interior adjusting 55 rod m^4 . The latter at its outer end has threaded engagement with the rotary sleeve m^5 , which can be turned by the crank handle to effect adjustment of the friction roll toward or from the center of the friction disk, 60 thereby providing a variation in the driving speed.

Movement is transmitted, through the bevel pinion m^7 secured to the friction disk, to the bevel gear m^8 , the latter secured to the 65 sleeve m^9 , which is concentric with but ro-

tatable about the shaft h . From the sleeve m^9 driving movement is imparted (Figs. 1 and 2) through the pinion m^{10} and intermeshing gear m^{11} to the bevel gears m^{12} and the inclined shaft m^{13} , at the upper end of 70 which is the bevel gear m^{14} engaging with a driven gear m^{15} upon the end of the knotter lead screw m^{16} . A constant rotary movement of the lead screw is thereby occasioned, dependent in rate upon the position of the 75 friction roll m^2 . The adjustment of the latter is readily effected by the hand wheel and can be accurately gaged by reference to the overlying fixed scale m^{17} , (Fig. 1) which may be suitably graduated, with reference 80 to the spacing of the warp threads, so that the operator can readily move the friction roll to the position corresponding to the required speed.

Referring now to the means for communicating movement from the lead screw to the warp-carriage-adjusting mechanism, the former is provided (Figs. 6-9) at the end opposite its attachment to the bevel gear m^{15} with a cam n , which, once for each rotation 90 of the lead screw, engages with the end of a pivoted arm n' , causing depression of the rod n^2 , which is adjustably secured to the opposite end of the said arm. The rod n^2 is normally elevated by the spring n^3 which 95 presses the arm n' toward the cam n , and is jointed at its lower end to the swinging pawl arm n^4 , fixedly attached to the pin n^5 , the latter being journaled in the end of the swinging supporting arm n^6 , and having attached at its opposite end the pawl n^7 . Downward movement of the rod n^2 swings the nose of the pawl into engagement with the edge of the knurled or finely toothed disk n^8 , which is pinned or otherwise secured to the stud which carries the shiftable 100 compensating pinion l^4 . The first depression of the rod n^2 swings the pawl arm n^4 down and away from its adjustable stop screw n^9 until the pawl nose engages the disk. Movement of the swinging supporting arm n^6 , which is journaled upon the disk shaft, is opposed by the friction created by the spring-pressed plate n^{10} , so that the pawl arm 105 swings with greater freedom than the supporting arm. When the pawl grips the disk, however, further movement of the cam swings the pawl arm, supporting arm and pawl as a unit, causing movement of the toothed disk and the compensating pinion 110 l^4 . As the cam n drops away from the arm n' , retraction of the rod is caused by the tension spring n^3 , providing first a release of the pawl and then a return of both the supporting arm and the pawl arm to the position shown in Fig. 9, with the latter against the stop screw n^9 . By adjusting the stop screw n^9 or the position of the point of attachment of the rod n^2 to the lever n' the movement given to the warp carriage may 115 120 125 130

be varied to any desired extent within certain limits.

It will be observed that excepting when the cam is acting through the pawl to move the worm and the warp carriage, the pawl is disengaged from its toothed disk and the carriage is free to be positioned by hand, if desired. There is here provided means for manually positioning either warp carriage, the same comprising the sprocket chain connection o (Fig. 7) which connects the sprocket wheel o' upon the hand rod shaft l^8 with the sprocket wheel upon the shaft carrying the pinion l^4 . By this means, the manual turning of the hand rod will give a slight compensating movement to that carriage with which the compensating pinion is in engagement. By moving the hand rod up or down, this compensating movement may be impressed upon either warp carriage at will.

In practice, the slay of the narrower warp being known, the advance of the uniting mechanism and the degree of differential movement will readily be adjusted within all the limits of precision which practical conditions permit through means of the variable speed friction drive. Irregularities in the spacing of the warp threads, however, frequently occur, for which a fixed adjustment of the driving mechanism cannot provide. A judicious use of the hand compensating movement by the operator with reference to accidental or irregular spacing of the warp threads in the practical operation of the machine, is frequently of advantage.

The warp separating and selecting device itself is also adapted to supplement the above described mechanism in correcting or compensating more or less for localized irregularities or spacing in the individual threads of warp. Since the warps may be adjusted to crowd the leading unseparated threads thereof toward and against the leading end of the thread selecting screw, the threads engaging first the inclined nose thereof are brought into an approximately parallel relation under an increasing tension. This tends to bring them in a closely arranged evenly faced flat, stretched sheet when they reach the cylindrical portion of the sleeve and before they encounter the selecting lip.

Referring now more particularly to the uniting mechanism, which in the machine illustrated I have embodied in the form of knotting means, the same is mounted upon the carriage P (Figs. 11, 12 and 13), which is adapted to slide upon suitable guide-ways P' extending between the two swinging frame members. This carriage is provided with a split nut p adapted to be opened or closed by the lever arm p' and thereby engaged with or disengaged from the lead screw m^{16} .

During the operation of the machine, while the carriage is continuously advancing, a suitable placing member acting transversely, the threads seizes the two foremost selected and separated threads of the parallel warps which are in the general relation with reference to the knotting mechanism shown in Fig. 10, and places the same in the hooked end of the knotter. The knotter then turns to form the loop, separates to receive the strand which is laid in by the placing member, the end is severed, the loop stripped from the knotter over the held severed end by means of a stripper arm, which latter then acts to hold the knotted end while the knot is further tightened by a tensioning member acting below the same. As soon as the knot is tightened, suitable stripping devices act to cast aside both the two severed ends and the double united end to prevent interference with the subsequent action of the knotter upon the two succeeding threads.

Referring more particularly to the details of construction, there is provided a placing member or thread guide q , here in the form of a drawing needle with an appropriately formed hooked eye, which needle is given a compound movement by the following mechanism: The needle is mounted to reciprocate longitudinally in supporting arms q' which are secured to the slide q^2 , adapted to slide transversely to the axis of the needle. This slide is reciprocated by the bell crank lever q^3 , which is moved by the actuating arm q^4 , jointed to the upright pivoted lever q^5 , which latter has at its lower end a pin q^6 , engaging the face of an appropriately faced cam q^7 . This cam, like the other operating cams for the knotting mechanism, is keyed to the splined driving shaft g so as to be turned thereby while slidably lengthwise the same with the knotter carriage. Combined with the lateral movement of the needle, longitudinal reciprocatory movement is imparted thereto by the swinging arm q^8 , pivoted at q^9 , and jointed to the actuating lever q^{10} , the latter being in turn jointed to the upright arm q^{11} , which is actuated in turn by the underlying cam q^{12} .

The knotting device may be of any suitable construction, but herein comprises (Fig. 19) the knot-forming member r (Fig. 19) in the form of a hook, secured to the rotary sleeve r' , mounted in bearings upon the carriage, said sleeve and hook being journaled for rotary movement only. The rear end of the sleeve has keyed thereto the small pinion r^2 , which is adapted to engage with the segmental gear r^3 (Fig. 12) pivoted at r^4 upon the carriage and having a depending arm provided with a pin r^5 adapted to engage with the appropriately formed groove of a cylinder cam r^6 , rotation of the latter thereby effecting a reciprocatory rotative movement of the knotter.

sleeve and loop-forming hook r . Combined with the loop-forming hook r is the separating member r^7 , also in the form of a hook, and normally retracted to register 5 with the looping hook but connected within the sleeve to a stem r^8 . The latter is adapted to be pressed forward against the compression spring r^9 by the forward movement of the plunger rod r^{10} , this causing 10 the separation of the two hooks. The plunger rod r^{10} at the appropriate time is pressed forward by the movement of the pin r^{11} carried upon the inclined arm r^{12} (Fig. 12) of the pivoted lever r^{13} , the latter actuated 15 by the cam r^{14} . The separating hook r^7 while having a separating movement relative to the loop hook r , is caused to turn therewith through the pin r^{15} working in the longitudinal slot r^{16} . While I have 20 termed the members r and r^7 hooks, this will be understood as having reference to any members constructed for like functions though of quite different formation or shape. The hooks r , r' constitute a 25 rotatable tying bill.

At the beginning of the knotting operation the needle or thread guide q moves from the position which is represented in Fig. 17 to a position shown in full lines 30 in Fig. 14, with its sides against the two foremost, parallelly arranged warp threads represented at x , x . The needle is then caused to retract in the path shown in dotted lines and into the position also shown 35 in dotted lines, by which movement it is caused to seize the two foremost threads and lay them into the bight of the knotter hook or rotatable tying bill, the ends of the threads slipping through the friction 40 clamp in which they are held to provide the needed slack without however being pulled free therefrom.

The next stage in the operation is indicated in Fig. 15, where the knotter hook 45 or rotatable tying bill has undergone half a revolution, the needle moved slightly to the left, and an underlying tension rod s swung outwardly to put a slight yielding tension on the two strands where they 50 underlie the knotter. The tension rod s is mounted in a socket arm s' , pivoted at s^2 and jointed to the actuating rod s^3 , which latter in turn is journaled to the upright, cam-actuated lever s^4 , the tension being 55 placed on the thread by the spring s^6 connected to the rod s^3 and acting to swing the rod outward when the actuating cam permits.

As the knotting device or tying bill completes its revolution (Fig. 16) the separating hook is caused to advance and the needle or thread guide q is caused to move forwardly and laterally to assist in laying the overlying strands into the separation 65 between the two hooks of the tying bill.

Thus the said thread guide q functions to move or place the threads in position for action thereon by the open tying bill. At the same time the tension rod s is retracted to relieve the tension on the underlying 70 strands, so that as the separating hook retracts, as it does as soon as the strands are inserted, the loop formed is comparatively slack. The separating hook in retracting holds clasped the inserted strands and in 75 that position (shown in Fig. 17) the strands are severed close to the hook by a severing device t .

The latter may be of any suitable construction but preferably has a rotary movement and is constructed to give the strands a drawing cut. In the disclosed embodiment of my invention the severing device comprises the sickle-shaped blade t (best shown in Fig. 18), secured to the end of the rotary 80 spindle t' and adapted at the appropriate time, as shown in Figs. 17 and 18, to sweep across the end of the knotter and sever with a drawing cut the overlying strands, which are then held taut by the needle and the 85 knotter hooks. The spindle t' is journaled parallel with the knotter and carries at its rear end the small gear t^2 , which meshes with the pinion t^3 upon the end of the knotter 90 sleeve r' , so that as the latter is respectively 95 rotated the blade swingingly reciprocates in the general direction of the threads, across the end of the knotter but without effect until the right time, when the threads are appropriately positioned by the needle. 100

Following immediately the severing of the thread ends the knotter continues to turn for about half a revolution into some such position as shown in Fig. 18 and at the same time the swinging loop-stripping arm u 105 moves in, as shown in Fig. 17 and in elevation in Fig. 18, to strip the loop from the knotter and slip the same over the severed but clasped end. The stripper arm (Fig. 11) is pivoted at u' upon the carriage and jointed to the actuating rod u^2 , which latter is retracted by the spring u^3 but normally pushed forward by the upright cam-actuated lever u^4 to maintain the tension arm outward. The extreme end of the stripper 115 arm has a small hook u^5 , which catches the underlying strands of the thread as it swings in and draws them taut to strip the loop off the knotter and over the severed end, the knotter or rotatable tying bill at that time 120 having its bill depending or pointing in the general direction in which the threads are held as shown in Fig. 18. The accuracy and precision of the stripping action is assisted by the inwardly and downwardly inclined 125 guide plate v , which, as the stripper draws the strands inwardly, tends to direct them and align them beneath the knotter, so that a certain and efficient stripping of the loop is better assured and at the same time the 130

threads are substantially clamped by the co-operating action of the stripper arm *u* and the guide plate *v*.

As the loop is stripped over the end, the latter being clasped between the knotter hooks tends to draw the knot tight, but further and final movement of the stripper arm pulls the free end from the knotter.

To still further tighten the knot, which it will be observed is now formed close to the severed ends, the outer face of the carriage plate against which the stripper arm swings is beveled or shaped (see Fig. 19) to correspond to the inner face of the stripper arm, so that as the latter completes its movement it holds the knotted end between its inner face and the outer face of the carriage plate. At the same time the underlying tension rod *s* gives a sharp, quick, outward stroke to pull the underlying strands and further to tighten the knot.

The stripper arm then moves out again to the position shown in Fig. 14, the tension arm back to the position there shown, the knotter also returning to its initial position. The needle then moves laterally from the position shown in Fig. 17 to that in Fig. 14 to repeat the knotting operation.

The knotted ends and the severed ends, however, at completion of the operation are stripped or displaced to clear the way for the next action of the knotting mechanism. The severed end of the old warp, which is held by the clamping rod *b*¹⁰, and hangs down over the separating screw *d*, is cast backward by a mechanically operated swinging displacing arm *w* (Figs. 11 and 12) which is secured to the end of a short shaft *w'*, journaled upon the carriage parallel to the needle and knotter. The opposite or rear end of this shaft has the pin *w*², which is jointed to the upright lever *w*³, pivoted upon a carriage *w*⁴, and pressed against the face of the actuating cam *w*⁶ by the spring *w*⁶. The arm *w* has quite a range of upward movement between the clamp *b*¹⁰ and the separator rod and its actuating cam permits the spring to give it a quick, sharp throw upwardly just after the knot has been formed and the end severed, to strip the short severed end from the separating screw and throw it over and back of the clamping rod.

While the displacement of this severed end is effected mechanically, other means might be employed. For the stripping or displacement of the knotted end and the remaining short severed end, I have shown other than mechanical means, herein pneumatic. Referring to Fig. 11, there is provided the nozzle *x*, which is properly shaped and positioned to direct an air blast upon the severed end of the remaining warp when the knot has been tied and strip or displace the same from the separator shaft *e*. Underlying the nozzle *x* is a second air nozzle

x', which at the same time when the knot has been tied and the loop-stripper arm withdrawn, directs an air blast against the knotted strands to blow them down and away from the knotting mechanism.

For the production of the two air blasts, at the proper time the two nozzles are connected to a common air conduit *x*² leading to the air chamber *x*³, which is provided with a valved orifice and a valve *x*⁴ controlling the same. The air chamber is provided with air through the conduit *x*⁵, which (Fig. 2) is connected by the flexible pipe coupling *x*⁶ (Fig. 2) with the air pipe *x*⁷ at the end of the machine. The latter leads from a receiver *x*⁸ in which a constant air pressure of suitable amount is maintained through connections *x*⁹ with the air pump *x*¹⁰, the latter being driven from the driving gear *x*¹¹ upon the main driving shaft *x*'.

At the appropriate time the air pressure, which is constantly maintained in the receiver *x*⁸, is momentarily admitted to the conduit *x*² and the two nozzles through a short, quick movement of the valve *x*⁴, which is effected through the valve-actuated rod *x*¹², controlled by the pivoted arm *x*¹³ and the actuating cam *x*¹⁴.

The air receiver *x*⁸ is provided with a relief valve *x*¹⁵, which is adapted to relieve the pressure therein when it reaches a predetermined amount. The relief valve therefore in connection with the pump provides means for maintaining a substantially constant pressure in the receiver.

The construction of the knotter shown is especially simple and convenient, since the two hook-shaped members while normally confined within the rotary sleeve, may be readily withdrawn as a unit therefrom by merely unscrewing the threaded cap shown in Fig. 19.

While I have shown and described one form of my invention, it will be understood that the same is not limited to the details herein disclosed, or to the specific means herein described for securing adaptability of the action of the knotting mechanism to the irregular or different spacing of the warp threads, or to the specific adaptation herein made of various features of the invention, but that extensive modifications may be made therein without departing from the spirit of my invention.

Claims:

1. A warp-uniting machine having means for supporting a pair of warps, warp-uniting mechanism, means for causing progressive relative movement between the warps and said uniting mechanism, means for causing relative compensating adjustment between the uniting mechanism and a warp support, and means for throwing in or out of operation said adjustment causing means with reference to either warp support.

120

125

130

2. A warp-uniting machine having warp-uniting means, means for supporting a pair of warps, motive means for adjusting the relative position of the uniting means with reference to the threads of either warp, and means whereby the motive means may be placed in operative relation to either warp carriage. 70
3. A warp-uniting machine having warp-uniting means, means for supporting a pair of warps, motive means for adjusting the relative position of the uniting means with reference to the threads of either warp, and means whereby said motive means may be thrown into engagement with reference to one warp support and out of engagement with reference to the other. 75
4. A warp-uniting machine having warp-uniting means, means for supporting a pair of warps, compensating mechanism for adjusting the position of either warp support relatively to the uniting means, a shiftable gear for applying said mechanism to the adjustment of either warp support; and means whereby said gear may be shifted. 80
5. A warp-uniting mechanism having means for supporting a pair of warps, warp thread adjusting mechanism, means for mechanically operating said mechanism, means also for manually operating the same, and means for placing said mechanism in operative relation with reference to either warp support. 85
6. An organized machine for tying warp threads having in combination devices for supporting two warp sections, thread tying mechanism, two sets of warp thread engaging devices adapted to act progressively to engage with the threads of the respective warps and present successive pairs of threads one from each warp to the tying mechanism, and instrumentalities to compensatingly adjust the relation of the thread engaging devices to the foremost unjoined threads. 90
7. A warp-uniting machine having warp-uniting means, a plurality of warp supports, shiftable means for adjusting the position of said uniting means relatively to either of said warp supports, and manually operable means for shifting said adjusting means and also for operating the same. 95
8. A warp-uniting machine having warp-uniting means, compensating means, manually operable means adapted, when moved in one direction, to place said compensating means in operative relation to one warp, when moved in the opposite direction, to place the same in operative relation with reference to the other warp and, when turned, to actuate said compensating means. 100
9. A warp-uniting mechanism having warp-uniting means, means for supporting a pair of warps, compensating means, driving means, and rotatable manually operable means adapted when turned to actuate said compensating means, when moved laterally to change the operative relation of said compensating means and the warp supports and when shifted axially to control the said driving means. 105
10. A warp-uniting machine having an upright support, a swinging head thereon and warp-uniting mechanism upon said head. 75
11. A warp-uniting machine having a support, warp-uniting mechanism thereon, and means permitting the adjustment of said mechanism to an upright position to facilitate movement of the machine and permitting also its adjustment to a laterally displaced position to overhang a loom. 80
12. A warp-uniting machine having a base or supporting member and warp supporting parts upon said supporting member, said parts being laterally adjustable with reference to the base whereby they may be sustained above the same for facility in moving the machine or moved over or toward a loom for facility in operation. 90
13. A warp-uniting machine having a supporting member, a warp holding means, warp-uniting means, and means for adjusting said holding means and uniting means upon the supporting member, said adjusting means including a worm and a worm gear. 95
14. A warp-uniting machine having a base, a head adjustably mounted thereon for swinging movement, warp-holding means and warp-uniting means upon the head and driving means for the same upon the base. 100
15. A warp-uniting machine having warp-uniting means and means, including a flexible driving member, adapted for connection with a driven member upon an adjacent loom for driving the warp-uniting means. 105
16. A warp-uniting machine having warp-uniting means, a driving shaft extending from either end thereof, and a driving coupling adapted to be placed upon either of said shaft ends and to be coupled about an adjacent driven element. 110
17. A warp-uniting machine having warp-uniting means, means for causing relative movement between the uniting means and warp threads to permit the progressively advancing action of the former upon the latter, and variable speed transmission means to adjust the rate of movement according to the spacing of the warp threads. 115
18. A warp-uniting machine having warp-uniting means, means for causing relative movement between the uniting means and the warp threads, variable speed transmission means, a gage, and means to adjust said transmission means with reference to the gage and according to the spacing of the warp threads. 120
19. A machine for operating upon warp 130

- threads having an operating mechanism, means for causing progressive relative movement between the operating mechanism and the warp, means for causing a compensating movement between the operating mechanism and the warp from one end thereof to the other, and means for adjusting the rate of said movements to correspond to the spacing of the warp threads.
20. A warp uniting machine having warp-uniting means, means for causing relative movement between the uniting means and the warp threads to permit progressively advancing action of the former upon the latter, and variable speed transmission means for adjusting the relative movement according to the spacing of the warp threads, said means comprising a friction roll, a friction disk, and means for adjusting the roll to contact with the disk at different radial distance from its center.
21. A machine for operating upon warp threads having operating mechanism, means for causing progressive relative movement between the operating mechanism and the warp from one end thereof to the other, and means for adjusting the rate of movement to correspond to the spacing of the threads.
22. A knot tying mechanism having a knotter provided with a rotary looping hook, a hook rotatable therewith but separable therefrom, means to hold the strands while the loop is formed and thereafter to lay the strands between the looping hook and separating hook, and means thereafter to sever the strands between the knotter and the holding means.
23. A knot tying mechanism having a knotter, rotary strand severing means moving in the general direction of the threads during engagement of the latter by the knotter, and means for moving the threads into the path of the severing means after the formation of the loop by the knotter.
24. A knot-tying mechanism having means for holding distended two sets of warp threads, knotting means and means for positioning a pair of threads for engagement with the knotting means, said positioning means being movable during the tying of the knot with reference to the knotting means.
25. Means for knotting together separate threads comprising in combination means to support two distinct and separate threads each at a plurality of separated points in parallel relation, a rotatable tying bill, means for opening and closing said tying bill, and means for effecting the moving of two separate and distinct threads into the path of the open tying bill.
26. A thread-tying mechanism comprising a rotary looping hook, a separating hook adapted to rotate therewith but separable therefrom, positioning means adapted to lay a thread into the rotary looping hook for the formation of a loop and by further movement to assist in the laying of the thread between the separating hook and the looping hook preparatory to the stripping of the loop.
27. A warp-uniting machine having means for holding distended two sets of warp threads, knot tying means, a drawing needle for selecting a thread from each warp and drawing the selected pair into engagement with the knot tying means, and means for moving said needle with reference to the knot tying means during the tying of the knot to assist in forming the latter.
28. An organized warp uniting machine having in combination thread uniting mechanism, the latter including a rotary tying member, devices for holding two unleased warp sections, independent thread separating means for engaging and separating the threads of the two warp sections, and a common thread engaging device for engaging and taking two separated threads, one from each warp.
29. A knotting mechanism having devices to hold a pair of threads in operative relation to a tying bill, a tying bill mounted to turn about an axis, mechanism to open said bill, a thread guide plate located transversely of the threads, a hooked stripping member with mechanism to impart to the same a knot-stripping movement across and in close proximity to the thread guide plate and from the opposite side of the threads against the threads to draw the latter by a wiping action across the edge of the plate, and means to hold clamped the thread portions which extend beyond the plate on the opposite side thereof from the stripper.
30. Knot tying mechanism comprising in combination means separately to support two distinct and separate threads each at a plurality of separated points and in a spaced relation with respect to each other, a knot tying device having a rotary tying bill, devices to take said two threads from their defined position of spaced relationship and to bring them together in operative relation to said tying bill, mechanism to open said bill, a thread guide plate located transversely of the threads, a hooked stripping member mounted to turn on an axis and having mechanism to impart to the same a knot-stripping turning movement to move the same across and in close proximity to the thread guide plate and from the opposite side of the threads against the threads to draw the latter by wiping action against the edge of the plate, and means to hold clamped the thread portions which extend beyond the plate on the opposite side thereof from the stripper.

31. A knot tying mechanism having a knotter for forming a loop in a thread strand, means for positioning said strand with reference to the knotter, means for tensioning the strand during the formation of the loop, while slackening the tension after the formation thereof to assist the stripping of the loop from the knotter. 5
32. A warp-uniting machine having means for holding distended a series of warp threads, knotting means, means for positioning a pair of threads with reference to the knotting means, and additional means for tensioning said threads during the knot-tying operation. 10
33. A warp-uniting machine having means for holding distended a series of warp threads, knotting means, means for positioning a pair of threads with reference to the knotting means, and a variable tensioning device for changing the tension upon the threads during the knot tying operation. 20
34. In a knot-tying mechanism, in combination, thread holding means, a rotatable tying bill rotatable about an axis transverse to the general direction in which the threads are held, a thread guide, a stripping means located between said bill and said guide and means for moving said stripping means 25 against the threads to strip the knot from the bill when the latter reaches a position pointing approximately in the general direction in which the threads lie, thereby to wipe the knotted ends into the space between said stripping means and said guide. 30
35. In a knot tying mechanism, the combination with a knotter having rotary separable loop-forming members, of positioning means for positioning a pair of threads with reference thereto, thread tensioning means adapted to tension the threads during formation of the loop but to slacken the tension on the formation thereof. 40
36. In a knot tying mechanism, the combination with a knotter having rotary separable loop-forming members adapted to separate to receive and hold the strands between them after the formation of the loop, tensioning means to tension the strands during the formation of the loop but to slack the tension on the loop after the strand has been seized between the separable members. 50
37. In a knot-tying mechanism, the combination with loop-forming means, means to seize the thread and hold the same after formation of the loop preparatory to the stripping of the loop over the held thread, means for tensioning the thread to assist in forming the loop, while slackening the tension on the loop on the seizure of the thread. 55
38. A knot tying mechanism having knotting means comprising means for forming a loop in a pair of threads, means to seize the thread and hold the same after formation of the loop and preparatory to the stripping of the loop over the held threads, means for tensioning the threads to assist in forming the loop, while slackening the tension on the loop on the seizure of the threads, and means for severing the threads adjacent the held ends. 70
39. A knot-tying mechanism having loop-forming means, means for seizing the thread and holding the same after the formation of the loop preparatory to the stripping of the loop over the held thread, means for positioning the thread for engagement by the loop-forming means, and means for severing the held thread between the holding means and positioning means after the formation of the loop. 75
40. A knot-tying mechanism having loop-forming means, means for seizing the thread and holding the same after the formation of the loop preparatory to the stripping of the loop over the held thread, means for holding the threads with reference to the loop-forming means, means for stripping the loop over the held thread end, and means for drawing the thread strand while the formed knot is held by the stripping means to tighten the knot. 80
41. A knot-tying mechanism comprising a rotatable tying-bill arranged to be opened and closed, mechanism to open and close the tying-bill, a thread guide and a stripper pivoted to turn about an axis and move across the path of the threads engaged by the tying-bill to engage the threads beyond the knot and wipe them against the guide at one side of the axis of the tying bill and into the intervening space thereby stripping the knot by the resultant pull on the threads. 90
42. A warp-uniting machine having means for holding distended two sets of warp threads, knot-tying means, means for positioning a pair of threads with reference to the knot-tying means, movable knot stripping means and stationary guiding means co-operating therewith. 100
43. A knot tying mechanism comprising a rotatable tying bill having means to open and close, guide means to position the thread ends to be engaged by the tying bill in the initial formation of the loop, means to turn the tying bill, means to open the same, means to move said guide means to place the thread ends between the parts of the open tying bill, means to sever the thread ends close to the end of the tying bill and means to tension the thread ends. 110
44. A knot-tying mechanism having thread-holding means, knot-forming means, a swinging knot stripper, and a swinging tension bar co-operating therewith. 115
45. A knot tying mechanism comprising a rotatable tying bill having jaws to open and close, guide means to position the thread ends to be engaged by the tying bill in the initial formation of the loop, means to turn 120
- 125
- 130

the tying bill, means to open the jaws of the tying bill, means to move said guide means to place the thread ends between the jaws of the open tying bill, means to sever the thread ends close to the jaws of the tying bill, means still further to turn the tying bill, a stripper, and means to move the same at about the same time as the last mentioned turning movement of the tying bill, to strip the loop over the ends held by the tying bill.

46. In a knot-tying mechanism the combination with knot-tying means, of pneumatic stripping means for displacing the thread ends.

47. In a knot-tying mechanism, the combination with knot-tying means, of thread severing means, and pneumatic means for displacing the severed ends.

48. In a warp-uniting machine, the combination with means for holding in close proximity the threads of two warps, thread-uniting mechanism, of thread severing means, and pneumatic means for displacing the severed ends.

49. In a knot tying mechanism, the combination with thread uniting means, of pneumatic means for displacing the united ends.

50. In a knot tying mechanism, the combination with thread-tying means, of severing means, pneumatic means for displacing knotted ends, and pneumatic means also for displacing severed ends.

51. In a knot tying mechanism, the combination with thread-uniting means, of thread-severing means, pneumatic means for displacing one severed end, and mechanical means for displacing the other severed end.

52. A machine for operating upon warp threads having driving means for giving a relative traversing movement between the operating means and the warp from one end thereof to the other and variable speed transmission means for adjusting the rate of movement of said driving means with reference to the spacing of the warp threads.

53. A warp uniting machine having thread - uniting means, thread - severing means, pneumatic stripping means coöperating therewith, and pressure-creating means for supplying pressure to the pneumatic stripping means mounted upon the machine and driven therewith.

54. A knot tying mechanism having pneumatic thread-stripping means for displacing the thread ends and valved means for suitably timing the action of said stripping means.

55. A warp - uniting machine having pneumatic thread-stripping means, for displacing the thread ends, pressure creating means upon the machine and driven there-
with, an air receiver connected to said strip-

ping means and said pressure-creating means, and means maintaining a substantially constant pressure in said receiver.

56. In a warp-tying machine the combination with a traveling carriage bearing knotting mechanism, of means for independently supporting the warps to be tied, and means for positively moving each of said warp supports relatively to the knotting mechanism and differentially with reference to each other.

57. The combination with warp-tying means, of thread-placing means, means for supporting a pair of warps, means for separating the threads thereof prior to the action thereon of said thread-placing means, and means for giving compensating adjustment to the position of the warp-tying means relatively to the warp.

58. In a warp-uniting machine the combination of warp-uniting means, of means comprising a rotary knotter for causing relative movement between the same and the warp threads to permit progressively advancing action of the former upon the latter, thread-drawing means for positioning the threads relatively to the knotter, thread-separating devices for separating the same prior to the action of the drawing means and means for causing relative compensating adjustment between the knotter and the warp threads.

59. In a warp-uniting machine the combination of warp-uniting means, of means comprising a rotary knotter for causing relative movement between the same and the warp threads to permit progressively advancing action of the former upon the latter, thread-drawing means for positioning the threads relatively to the knotter, thread-separating devices for separating the same prior to the action of the drawing means and means for causing relative compensating adjustment between the threads of the two warps.

60. A warp-uniting machine having warp uniting means, means for supporting a pair of warps, means for causing the travel of said warp-uniting means along the threads of said warps, and means for manually adjusting one of said warps while the other remains stationary.

61. The combination with means for supporting two threads at two points in their lengths, of means located between said supporting means for forming a knot, and a stripping member mounted to turn on an axis also located between said supporting means, means coöperating with said stripping member to clamp the knotted threads and mechanism to move said stripping member to engage the threads beyond the knot and clamp the same and remove the knotted ends from said knot forming means by the resultant pull on the threads.

62. An organized knot tying mechanism comprising in combination means to support two distinct and separate threads each at a plurality of separated points, the threads 5 being in a general parallel but spaced relation with respect to each other, a knot tying device having a rotatable tying-bill with mechanism to open and close the same, means to take said threads from their defined position of spaced parallel relationship and to position them together in operative relation to the rotatable bill to be taken by the open bill during the rotation thereof and means to operate said tying-device to 15 tie said threads into a knot.
63. In a warp-tying machine, in combination, means for supporting two warps; a carriage; a thread selecting means and a tying mechanism mounted on said carriage; 20 and means for imparting a feed movement to one of said warp-supporting means with relation to the thread-selecting means.
64. In a warp-tying machine, in combination, means for supporting two warps; a 25 carriage; thread selecting means and a tying mechanism mounted on said carriage; means for advancing said carriage with relation to one of said warp-supporting means; and means for moving the other warp-supporting 30 means with relation to the carriage.
65. In a warp-tying machine, in combination, means for supporting two warps; a thread selecting means, a tying mechanism; means for actuating said selector mechanism; 35 and said tying mechanism, and for advancing them with relation to one of said warps; and means for moving the warp-supporting means for the other warp with relation to the thread-selecting means.
- 40 66. In a warp-tying machine, in combination, means for supporting two warps; a warp tying mechanism; means for advancing said warp tying mechanism with relation to one of said warps; means for actuating the warp tying mechanism; and means for moving the other of said warps with relation to the warp-tying mechanism.
67. In a warp-tying machine, in combination, means for supporting a warp; means 45 for taking a thread from said warp; means for tying together said thread and a thread from another warp; and means for moving said warp-supporting means with relation to said tying means.
- 55 68. In a warp-tying machine, in combination, means for supporting two warps; means for tying together two threads, one from each of said warps; and means for moving one of said warps with relation to 50 said tying means.
69. In a warp-tying machine, in combination, a bed; a pair of warp clamps upon 60 said bed; a warp carriage supported adjacent to said bed, and provided with a pair of warp clamps; and a warp-tying mecha-
- nism arranged to travel upon said bed between said clamps.
70. In a warp-tying machine, in combination, means for supporting two warps in substantially parallel planes, the threads of 70 each warp lying in the same plane; means for taking a thread from each of said warps; means for severing said threads; means for bringing said threads together, side by side, at a uniting means; and means 75 for uniting said threads.
71. In a mechanism for joining together the ends of two warps, in combination, means for selecting a thread from each of 80 said warps; means for separating said selected threads from their adjacent warp threads; means for uniting said selected threads by tying; and means for presenting the selected threads to said uniting means to be united.
72. In a warp tying machine the combination with means for supporting a pair of warps, of tying mechanism, severing means and pneumatic means for displacing the severed strands clipped from the knot. 85
- 90 73. In a warp tying machine, the combination with means for supporting a pair of warps, of tying mechanism, severing mechanism, driving means for the machine, and pneumatic means for displacing the strands severed from the knotted ends, said pneumatic means being also driven by said machine driving means.
74. An organized machine to separate threads singly from each of two warps each 100 of which has its component threads normally irregularly spaced in an unleased sheet and to tie together selected threads from each warp, said machine embodying in combination warp holding means to hold 105 crosswise sections of two such warps, a rotary knotter, a support therefor, feeding mechanism to cause a relative traverse between said support and said warp holding means lengthwise of the latter and crosswise 110 of the two warps, devices associated with said knotter and adapted during said traverse successively and progressively to select threads singly from each of the warps and then to present the selected threads to the 115 knotter, and instrumentalities adapted to adjust to the spacing of the warp threads the action of the associated thread-selecting and conveying devices and knotter in their said relative traverse; thereby to insure the 120 progressive and successive selection of pairs of threads, one from each warp, and the progressive presentation of such selected threads to the knotter and to compensate for the varying spacing of the threads of each 125 warp and for the variance of the two warps in total widths thereof.
75. An organized machine for tying the ends of warp threads comprising in combination a plurality of warp supports for 130

holding unleased commercial warp sections, warp tying mechanism, feeding means for causing relative change of position between said supports and said tying mechanism to permit the latter to tie threads from a plurality of the warps, means to present threads that are to be tied operatively to said tying mechanism and compensating means to compensate for or adapt the action of said presenting means to, the varying relation of said warp threads on the several supports.

76. An organized machine for tying together the threads of unleased warps comprising in combination supporting devices to hold the crosswise sections of two such warps, operating mechanism including warp tying mechanism adapted to act progressively upon the threads of the two warps, feeding means to cause relative traverse between the warp supports and the operating mechanism, devices to present successive pairs of threads one from each warp to the tying mechanism, and compensating means to compensate for the difference in position of successive threads of the two sections with relation to the operating mechanism in the course of its progressive action.

77. An organized machine for joining together the threads of unleased warps comprising in combination supporting devices for holding the cross-wise sections of two such warps, knotting mechanism adapted to act progressively upon the threads of the two warps, feeding means to cause relative traverse between the warp supports and the knotting mechanism and compensating means to compensate for the difference in position of the successive threads with relation to the knotting mechanism.

78. An organized machine for tying together the threads of unleased warps comprising in combination supporting devices to hold the sections of two such warps, warp tying mechanism adapted to act progressively upon the threads of the two warps, feeding means to cause relative traverse between the warp supports and the tying mechanism, devices to present a pair of threads one from each warp to the tying mechanism and provision to variably and compensatingly adjust the action of said devices to the varying relation of the successive threads on the two supports to the tying mechanism in the course of such progressive action.

79. An organized machine for tying together the threads of unleased warps comprising in combination supporting devices to hold the crosswise sections of two such warps, warp tying mechanism adapted to act progressively upon the threads of the two warps, feeding means to cause relative traverse between the warp supports and the tying mechanism, and compensating means to compensate for, or adapt the action of

said mechanism to, the irregular spacing of the individual threads on said warp supports.

80. An organized machine for tying warps having in combination supporting means for supporting two warps sections, the threads of each warp section lying normally in substantially the same plane, thread taking mechanism for taking a thread from each of said warps, means for bringing said threads together at a tying device, a tying device for tying said threads and means to adjust the relation of the said devices to the foremost untied threads in a direction transverse the warps to adapt their action to any irregularity or difference of spacing of the individual threads in the two warp sections.

81. An organized machine for tying together the ends of two warps having in combination supporting means to hold the sections of two warps with the threads of each section unleased, operating mechanism to act progressively upon the threads of the two warps, feeding means to cause relative traverse between the warp supporting means and the operating mechanism, the latter including a rotary knitter, selecting means to select the threads one by one from the unseparated sheet of each warp, separating and placing devices to further separate the selected threads and to place them together side by side in operative relation to the knitter while providing slack in the ends to permit the action thereon of the knitter, severing means to sever the threads close to the knots, and means to displace the severed and the knotted ends from the knitter, said machine having also instrumentalities to adjust the relative action of the operating mechanism to irregularities or difference in spacing of the individual threads.

82. An organized machine for tying together the ends of two warps, having in combination supporting means to hold the sections of two warps with the threads of each section unleased, operating mechanism to act progressively upon the threads of the two warps, feeding means to cause relative traverse between the warp supporting means and the operating mechanism, the latter including a rotary knitter, selecting means to select the threads one by one from the warp sheet, thread placing means to place the threads side by side in operative relation to the knitter, and severing means to cut the threads beyond the knots, said machine having also compensating means to compensate for differences in spacing of the individual threads.

83. An organized machine for tying warp threads having in combination independent supports for the sections of two warps held stretched in unleased condition, the two sections being substantially parallel one to

- the other and one support being adjustable with relation to the other, a carriage, compactly arranged operating mechanism thereon, feeding means for traversing the carriage across said warps to permit the progressive action of the mechanism upon the threads thereof, said operating mechanism including knotting mechanism, a thread selecting device for each warp positioned to engage with the edge of the warp sheet, a separating device for each warp adapted to further separate the selected threads a substantial distance from the unseparated portions of the respective warps, thread placing means common to both warps to bring together a pair of selected and separated threads one from each warp and place them side by side in operative relation to the knotting mechanism, thread severing means to sever the thread ends beyond the knots and pneumatic means for displacing the knotted ends from the knotting mechanism, the said machine also having compensating means to compensate for difference in the spacings of the individual warp threads.
84. In a warp tying machine the combination with thread tying mechanism, means to advance the same relatively across the warps to be united to permit the action thereof upon the warp threads and compensating means to compensate for any insufficient or excess advance of said tying mechanism relatively to the individual threads of the warp.
85. A warp tying machine having warp tying means, means for supporting a pair of warps, means for causing progressive action of the tying mechanism with reference to the threads of one warp and means for causing relative adjustment between the threads of the remaining warp and the position of action of the tying means.
86. In a warp tying machine the combination with two warp supports, warp tying mechanism, means to move the tying mechanism relatively to one support to traverse the warp supported thereon and means to adjust the other support relatively to the first support to maintain the required alignment between the warp threads and the tying mechanism.
87. In a machine for tying together the ends of two warps, in combination means for selecting a thread from each of said warps, means for tying said selected threads, means for advancing the tying means with relation to one of said warps and means for moving the other warp with relation to said tying means.
88. An organized machine for joining the ends of warp threads, having in combination holding means to hold the crosswise unleased sections of two warps, warp joining mechanism adapted to act progressively upon the threads of the two warps, feeding

means to cause relative traverse between the warp holding means and the joining mechanism, warp thread selecting means to pick off successive threads from each warp, thread placing means common to both warps to take a pair of selected threads one from each warp and place them together in operative relation to said thread joining mechanism and compensating means to compensate for differences or irregularities in the spacing of the threads of the two warps.

89. An organized machine for joining the ends of warp threads having in combination holding means to hold the crosswise sections of two warps with the threads of each section in unleased series, thread joining mechanism adapted to act progressively upon the threads of the two warps, feeding means to cause relative traverse between the warp holding means and the tying mechanism, a thread selecting device for each warp adapted to engage and pick off successive threads, separating means for each warp adapted to engage and further separate the selected threads each from the unselected threads of its section, and a thread placing device movable transversely the separated warp threads and adapted to engage the two separated threads and place them side by side in operative relation to said thread joining mechanism.

90. An organized machine for joining together the threads of two warps having in combination supporting means to support side by side two unleased warp sections, mechanism for operating progressively upon the warp threads, a support therefor, feeding means for causing relative traversing movement between the warp supporting means and the support for said operating mechanism, said operating mechanism comprising thread-joining mechanism, a thread-selecting device for each warp adapted to bear against the edge of the unseparated warp sheet and to pick off the threads one by one therefrom, separating means for each warp for engaging and further separating each selected thread from the unseparated threads of its warp section, and thread placing means common to both warps to bring said further separated threads together at said thread joining mechanism.

91. An organized machine for joining together the threads of two warps having in combination supporting means to support two unleased warp sections mechanism for operating progressively upon the threads, a support therefor, feeding means for causing relative traversing movement between the warp supporting means and the support for said operating mechanism, the said operating mechanism including thread joining mechanism, a thread selecting device for each warp adapted to bear against the edge of the unseparated warp sheet to pick off

the threads one by one therefrom, separating means to engage and further separate each selected thread from the unseparated threads of its warp section, a thread placing device movable transversely the separated warp threads and adapted to engage, bring together and place the two separated threads side by side in operative relation to the thread joining mechanism, and severing means to sever the threads beyond the jointures.

92. An organized machine for joining together the ends of warp threads having in combination warp holding means to hold stretched two unleased warp sections, warp joining mechanism adapted to act progressively upon the threads of the two warps, said joining mechanism including a rotary member, feeding means to cause relative traverse between the warp holding means and the joining mechanism, warp selecting devices to pick off the threads one by one from each warp, and thread placing means common to both warps to engage the two selected threads and bring them together in operative relation to said rotary tying member.

93. An organized machine for joining together the ends of warp threads having in combination warp holding means to hold stretched two unleased warp sections, warp joining mechanism adapted to act progressively upon the threads of the two warps, feeding means to cause relative traverse between the two supports and the joining mechanism, warp selecting means to select the threads one by one from each warp, means for engaging and further separating each selected thread from the unseparated threads of its warp section, thread placing means common to both warps and movable transversely the warp threads and adapted to engage, bring together and place the two separated threads side by side in operative relation to the thread joining mechanism, and severing means to sever the threads beyond the jointures.

94. An organized machine for operating upon warp threads having in combination supporting means for supporting a plurality of groups of warp threads, a rotary thread selecting device operatively related to each group and a common thread taking device for taking and bringing together the separate threads selected by the two selecting devices.

95. An organized machine for operating upon warp threads having in combination a plurality of rotary, warp-thread selecting worms and a common thread taking device for bringing together the separate warp threads selected by their respective warp worms.

96. An organized machine for operating upon the unseparated threads of an unleased

warp having in combination supporting means for supporting the sections of two such warps, operating mechanism, a support therefor, and feeding means, said operating means including two warp thread separating devices, each adapted to engage with threads of one of said warp sections and to select corresponding successive threads from the two warp sections, a warp uniting device and a common thread placing device adapted to engage selected threads and place them side by side in operative relation to said uniting device.

97. An organized machine for operating upon warp threads the same having in combination supporting means to support a warp, a warp selecting worm mounted in operative relation to said warps to select and separate successive threads thereof and driving mechanism to impart a movement of continuous rotation to said warp worm.

98. An organized machine for operating upon warp threads comprising in combination supporting devices to support a warp, rotatable thread selecting mechanism bearing against the edge of the unseparated warp sheet, thread taking means to take successive selected threads and driving mechanism to impart a movement of continuous rotation to said selecting and separating mechanism throughout successive actions of the thread taking means.

99. An organized machine for selecting and presenting warp threads to a thread taking device having in combination a continuously rotated thread selecting device bearing against the edge of the unseparated warp sheet, and intermittently operated thread taking device, to which warp threads are presented by the said thread separating device.

100. An organized machine for acting upon warp threads having in combination supporting means for supporting the stretched section of a warp, rotary thread selecting and separating means adapted to bear against the foremost stretched threads of said warp, a second supporting structure carrying said selecting and separating means, feeding means for causing relative traverse between said second supporting structure and the warp support, and driving means to impart a continuous movement of rotation to said thread selecting and separating means.

101. An organized machine for selecting and acting upon the stretched threads of a warp, having in combination thread operating mechanism and a continuously rotated thread selector in constant engagement with the leading unseparated thread.

102. An organized machine for uniting warps having in combination two warp supports, operating mechanism adapted to act progressively upon the warps across the

- width thereof, said operating mechanism including warp thread uniting devices and thread selecting and taking devices for selecting and taking away the threads in pairs 5 one from each warp and presenting them to the uniting mechanism, common power driven means to cause relative adjustment between the operating means and either warp support and means to apply said adjusting means to the adjustment of either warp at will.
103. An organized machine for uniting warps having in combination two warp supports, operating mechanism adapted to act 15 progressively upon the warps across the width thereof said operating mechanism including warp thread uniting means and thread selecting and taking devices for selecting and taking away the threads in pairs one 20 from each warp and presenting them to the uniting mechanism, common manual means to cause relative compensating adjustment between the operating means and either warp support and means to apply said manual adjustment to the adjustment of either warp at will.
104. A warp uniting machine having warp uniting means, means for compensating the position thereof relatively to the 30 warps and a single controlling device for effecting compensation with reference to either warp.
105. An organized machine for tying the threads of two warps having in combination 35 supporting means for supporting a pair of warps, knotting mechanism, devices for selecting and placing threads from the two warps in operative relation to the knotting mechanism, feeding means for causing relative traverse between said knotting and selecting and placing mechanism on the one hand and said warp supporting means on the other hand, and pneumatic devices for displacing the knotted ends.
106. An organized machine for joining the threads of two warps having in combination compactly arranged warp-thread-selecting and warp thread joining mechanism and pneumatic means to displace threads 50 from the vicinity of the joining mechanism.
107. An organized machine for operating successively upon the individual members of a series of warp threads, having in combination operating devices arranged to operate 55 successively and directly upon the individual threads and to throw off from said devices the free ends of such threads, and pneumatic instrumentalities arranged to move said free ends away from said devices.
108. An organized machine for operating successively upon the individual members of a series of warp threads, having in combination operating devices arranged to operate 60 successively and directly upon the individual threads and to throw off from said devices
- the free ends of such threads and pneumatic instrumentalities self contained with and energized by the machine, arranged to move said free ends away from said devices.
109. An organized machine for operating upon warp threads, having in combination supporting devices having members to hold a series of such threads stretched in substantially parallel relation, thread engaging devices arranged to engage the individual successive threads intermediate the thread-holding members and to disengage the threads successively from one of the members whereby the thread so disengaged is left with an end free, and pneumatic instrumentalities arranged to move said free ends away from said devices. 70
110. An organized machine for operating upon warp threads, having in combination supporting devices with members to hold a series of such threads stretched in substantially parallel relation, thread engaging devices arranged to engage the individual successive threads intermediate the thread-holding members and to disengage the threads successively from one of the members whereby the thread so disengaged is left with an end free, and pneumatic instrumentalities, self-contained with and energized by the machine, arranged to move said free ends away from said devices. 80
111. An organized machine for tying warps having in combination supports for a pair of warps, knotting mechanism together with thread selecting and placing devices 100 for selecting and placing threads from the two warps in operative relation to the knotting mechanism, feeding means for causing relative traverse between said knotting and selecting and placing mechanism on the one hand and said warps on the other hand, thread severing mechanism and pneumatic devices for displacing knotted ends and also severed ends. 105
112. An organized machine for uniting warp threads having in combination warp uniting mechanism, devices for holding clamped the ends of two warps, a movable support therefor permitting the machine to be placed adjacent a loom to receive the 110 clamped ends of the old and new warps from the latter while the warps are still held in the loom, and a flexible drive member adapted to connect the driving mechanism of the uniting machine with a driving member 115 upon the loom for driving the warp uniting machine. 120
113. An organized machine for uniting warp ends having in combination operating mechanism including warp thread tying devices, a support therefor, supports for two warps on which the warps are held in operative relation to the operating mechanism, feeding mechanism for causing relative traverse between the operating mechanism 125 130

and the warps to permit the progressive action of the former upon the latter, said tying devices including a rotary tying bill formed in two parts one adapted to separate 5 during tying of the knot to grasp the threads when the knot is stripped, devices to select the threads and convey them across the tying bill, and mechanism to strip the knot from the tying bill, said threads being held with 10 a yielding tension beyond the tying bill during the formation of the knot.

114. A knot tying mechanism comprising a rotatable tying-bill, mechanism to open and close the same, a thread guide acting to 15 guide the threads in the initial forming of the loop and to subsequently move the threads at a predetermined point in the rotation of the bill to lay the threads into the opened bill, and mechanism for moving said 20 guide.

115. Means for knotting together separate threads comprising in combination means to support two distinct and separate threads each at a plurality of separated points and 25 in parallel relation, a tying bill mounted to turn and to open and close, guide means to position the said threads to be engaged by the tying bill in the turning movement thereof in the initial formation of the loop, 30 means further to turn the tying bill and to open the same, and means to effect the placing of said threads in the open tying bill, as thus further turned.

116. A knot tying mechanism comprising 35 a rotatable tying bill, means to open and close the tying bill, and a thread guide having movement longitudinally of the axis of the tying bill to place the threads in the path of the open tying bill.

40 117. A knot-tying mechanism comprising a tying-bill mounted to turn on an axis, mechanism to open the bill, a thread guide for guiding the threads during the initial forming of the loop, mechanism subsequently 45 to move said guide to lay the threads into the opened bill at a predetermined point in the movement thereof, and means for holding clamped the thread portions extending beyond said bill on the opposite side thereof 50 from said guide.

118. A knot tying mechanism comprising a rotatable tying bill arranged to be opened and closed, a thread guide having movement longitudinally of the axis of the tying bill 55 to place the threads in position for action thereon by the open tying bill, and a thread clamp arm having movement transversely of the tying bill.

119. A knot tying mechanism comprising 60 in combination a rotatable tying bill having jaws adapted to open and close, a movable thread guide at one side of the tying bill adapted to receive both the thread ends preliminary to rotative movement of the tying 65 bill, a movable stripper at the opposite side

of the tying bill from said thread guide and a member at the same side of the tying bill as said stripper and co-operating therewith to clamp the threads and thereby to secure the drawing of the knot off the jaws of the tying 70 bill.

120. A knot tying mechanism comprising in combination a rotatable tying bill having jaws to open and close, a thread guide at one side of the tying bill adapted to receive both 75 the thread ends preliminary to rotative movement of the tying bill, and having movement subsequently to place the thread ends between the open jaws of the tying bill, a stripper at the opposite side of the tying 80 bill from said thread guide and movable in a plane transverse to the general direction of the threads, a fixed blade positioned in general parallelism to the said stripper when the latter engages the threads, said stripper 85 and blade coacting with the tying bill to effect the pulling of the loop of the knot off the tying bill and over the thread ends held in the tying bill, the tightening of the knot, and its final release from the tying bill. 90

121. A knot tying mechanism comprising a rotatable tying bill arranged to be opened and closed, a thread guide having movement longitudinally of the axis of the tying bill to move the threads into the path of the open 95 tying bill, and thread clamping and thread stripping means having movement transversely of the tying bill.

122. A knot-tying mechanism comprising a tying-bill mounted to turn on an axis, 100 mechanism to open the bill, a thread guide for guiding the thread during the initial forming of the loop, mechanism to move said guide to subsequently lay the threads into the open bill at a predetermined point 105 in the movement thereof, means for clamping the threads on the opposite side of the bill from the said guide, and a movable stripper for stripping the knot from the bill, said stripper being located between the bill 110 and said clamping means.

123. A knot tying mechanism comprising a rotatable tying bill arranged to be opened and closed, a thread guide having movement longitudinally of the axis of the tying bill to 115 move the threads into the path of the open tying bill, and combined thread clamping and thread stripping means having movement with respect to the tying bill.

124. An organized machine for tying 120 knots comprising in combination means separately to support two distinct and separate threads each at opposite sides of a knot tying device, a knot tying device having a rotatable tying bill with mechanism to open 125 and close the same, devices to displace said threads from their initial position of support and place them in position where they are held together across the bill and in operative relation thereto, a thread guide 130

- arranged transversely of the pair of threads and a stripping member arranged to move transversely of the threads between the tying-bill and the guide member and in close proximity to the latter to move the threads against the guide member and strip the knot.
125. A knot tying mechanism comprising a rotatable tying bill arranged to be opened and closed, a thread guide having movement longitudinally of the axis of the tying bill to move the threads into the path of the open tying bill, and a coöperating, movable tension arm to tension the threads.
126. An organized machine for tying knots comprising in combination devices to hold clamped two distinct and separate threads at separated points on opposite sides of a knot-tying device, a knot tying device having a rotatable tying-bill with mechanism to open and close the same, a movable thread guide for guiding the threads with relation to the rotatable bill during the forming of the loop, mechanism to move the guide to subsequently lay the threads into the open bill, a stationary thread guide on the opposite side of the tying-bill from the movable guide, and a movable stripper co-operatively related to the stationary guide to draw the threads against the same and strip the knots.
127. An organized machine for tying the ends of warp threads taken from different warps, comprising in combination a plurality of warp supports for holding unleased commercial warp sections;—thread tying mechanism;—feeding means for causing relative change of position between said supports and said tying mechanism thus to permit the latter, progressively and crosswise the warps, to tie threads from a plurality of warps;—means to take separately from the different warps and jointly to present threads that are to be tied operatively to said tying mechanism;—and traverse-governing devices to co-act with the said feeding means and the said means to take and present threads, and coöperatively to adapt the successive actions of the said thread-taking and presenting means, both to a varying successive relation of said warp threads on each support and to a varying position of the related threads on the different supports.
128. An organized machine for tying separate warps having, in combination, means for supporting two warp sections, the threads of each warp lying normally in substantially the same plane; a tying device for successively tying pairs of threads presented thereto; thread separating, assembling and feeding mechanisms for said tying device adapted, by relative traverse between said mechanisms and said warp supporting means cross-wise the warps, to bring together at said tying device pairs of threads successively, one from each warp, and progressively cross-wise the warps, and including traverse-governing devices arranged to adjust the operative relations of said last mentioned mechanisms, coöperatively, to any irregularity or difference of spacing of the individual threads in either warp.
129. An organized machine for tying separate warps having, in combination, means for supporting two warp sections, the threads of each warp lying normally in substantially the same plane; a tying device for successively tying pairs of threads presented thereto; and single-thread separating and assembling mechanisms for said tying device adapted, by relative traverse between said mechanisms and said supporting means crosswise the warps, to bring together at said tying device pairs of threads successively, one from each warp, and progressively crosswise the warps, and including traverse-governing devices arranged to adjust the operation relation of said last mentioned mechanisms, coöperatively, to any irregularity or difference of spacing of the individual threads in either warp.
130. An organized machine for tying warps having in combination supporting instrumentalities for supporting two unleased commercial warp sections, tying means for tying said threads and thread presenting means for presenting threads from said warp sections to said tying means, one of said means contributing to compensate the relation of said two means and the threads to be tied, in a direction transverse the warps to adapt their action to any irregularity or difference of spacing of the individual threads in the two warp sections.

In testimony whereof, I have signed my name to this specification, in the presence of two subscribing witnesses.

EDGAR F. HATHAWAY.
